CLAIM

The ornamental design for a modular toy bar, as shown and described.

DESCRIPTION

FIG. 1 is a perspective view of a first embodiment of a modular toy bar showing our new design;

FIG. 2 is a right side view thereof;

FIG. 3 is a left side view thereof;

FIG. 4 is a front view thereof;

FIG. 5 is a back view thereof;

FIG. 6 is a top view thereof;

FIG. 7 is a bottom view thereof;

FIG. 8 is a perspective view of a second embodiment of a modular toy bar showing our new design;

FIG. 9 is a right side view of FIG. 8;

FIG. 10 is a left side view thereof;

FIG. 11 is a front view thereof;

FIG. 12 is a back view thereof;

FIG. 13 is a top view thereof; and,

FIG. 14 is a bottom view thereof.

The broken lines in the drawings depict portions of the modular toy bar that form no part of the claimed design.

1 Claim, 8 Drawing Sheets
